UNITED STATES PATENT OFFICE

1,965,081

ICE MAKING APPARATUS

Joseph A. Martocello, Philadelphia, Pa.

Application September 14, 1931, Serial No. 562,671

8 Claims. (Cl. 62—159)

My invention relates to aerating connections for ice cans and to controlling valves for can basket units or a series of cans which are used individually in the manufacture of ice.

5 The main purpose of my invention is to provide controlling means to reduce the volume of air required after the cores have been pumped from the block of ice during their freezing period to eliminate ragged edges of ice formation at the top of the block.

A further purpose is to provide aerating systems used in the manufacture of ice with controlling valves to regulate the predetermined amount of air required after the core has been 15 pumped and refilled with fresh water.

A further purpose is to provide an adjustable air controlling valve for clear raw water ice making systems used at the end of a unit of ice cans when ice is being manufactured.

20 A further purpose is to provide a series drop tube bracket adapted to be clamped about a can basket lateral and having a curved arm between its clamping portion and its (free) tube carrier end.

25 A further purpose is to provide a spindle for a valve adapted to different size drilling of orifices, by previously spot drilling the spindle, to accommodate variation in air supply to aerating systems for the manufacture of ice.

30 A further purpose is to provide an automatic L shaped check valve for an aerating system in the manufacture of ice.

Further purposes will appear in the specification and in the claims.

35 I prefer to show one form only of my invention with a slight modification, selecting a form which is practical, efficient, reliable and inexpensive and which at the same time well illustrates the principles of my invention.

40 Figure 1 is a fragmentary perspective view of a raw water ice making system showing the parts in position.

Figure 2 is a top plan view of the structure seen in Figure 1.

45 Figure 3 is a side elevation of Figure 2.

Figure 4 is an enlarged sectional view of Figure 2 taken on the line 4—4.

Figure 5 is a side elevation partly in section of a check valve used in Figures 1 to 4 inclusive.

50 Figure 6 is an enlarged perspective view of a freeze-in drop tube bracket shown in Figures 1 to 4 inclusive.

Figure 7 is a section of Figure 6 taken on the 55 line 7—7 of Figure 6.

Figure 8 is a sectional view of an air controlling valve shown in Figures 1 to 4 inclusive.

Figure 9 is a sectional plan view of Figure 8 taken on the line 9—9.

Figure 10 is a detached perspective view of a 60 valve stem.

Figures 11 to 13 inclusive are sectional views of a valve stem showing different drillings that may be used to accommodate needed requirements of the controlling valve.

Figure 14 is a top plan view similar to Figure 2 but showing a modification.

Figure 15 is a side elevation of Figure 14.

In all figures like numerals refer to like parts.

Describing in illustration, but not in limitation 70 and referring to the drawings:

In describing first the invention as shown in Figures 1 to 4 inclusive, a header 20 is placed above a series of baskets 21 containing cans 22 and showing their relation to the flooring 23 of a 75 freezing tank. Air laterals 24 are attached to the header 20 by nipples 25 and L's 26.

The can baskets 21 may be placed in the openings formed between the lateral stringers 27 in the freezing tank beneath the flooring 23. These 80 can baskets carry a series of cans 22 in which ice is manufactured.

The freeze-in drop tubes 28 are supported by brackets 29 (see Figures 1 to 4 and 6, 7), which clamp at 30 about a supplemental or basket lateral 31 mounted upon the walls 32 of the basket.

The lateral 31 supports the brackets and also permits them to be rocked together about the lateral and to be locked in their normal position. This movement is controlled by an arm 33 terminating in a sliding plunger 34 which in normal position fits into an opening 35 in wall 32. The sliding plunger may be spring-pressed and is released by sliding a button 36 in an opening 37.

Air is supplied to the supplemental lateral 31 through valve 38, fitting 39 and flexible connection 40, seen in Figures 1 to 5. The valve body terminates in a threaded tap 41 fitting into the lateral. An opening 42 in the end of the 100 body admits a ball valve 43 but is then closed by a threaded plug 44.

The valve closes against a seat 45, as a check valve except when the fitting is inserted, at which time the valve is opened by the end 46 of a tapered 105 sleeve 47. The sleeve fits into a corresponding tapered seat 48 and the end 46 is laterally notched or otherwise relieved at 49 to permit air passage. The fitting 39 is adapted for tube connection.

The freeze-in drop tubes are held in place in the cans by screwing the upper ends 28' (Figure 6) of the tubes 28 into ferrules 50. The ferrules are provided with outwardly extending lugs 51 to fit in recesses 52 in the downwardly extending spaced curved arms 53, 53' of the bracket 29.

I countersink openings 54 in the ferrules 50 for easy reception of one end 55' of an elbow-10 nozzle 55 attached to the hose connection. The connections with the can basket lateral include flexible hose 56 and an L 57, one end of which is inserted within the lateral.

The bracket 29, which is split at 30 is fastened15 in place on the can basket lateral 31 by a set screw 58 as clearly shown in Figures 6 and 7. The clamp is reinforced by ribs 59, which merge into arms 53, 53'.

After a certain amount of freezing, the core20 removal takes place and as the continuation of aeration or agitation is desired, I provide for a reduction of air volume and for adjustment of the extent of variation also in many instances. This is effected by a controlling valve 63 shown25 in Figures 8-13.

The purpose of the controlling valve is to30 throttle down the pressure of air used for aeration, after the core has been pumped. The reduced volume of air is the more desirable as the water freezes because there will then be less35 agitation. An amount of air satisfactory during the earlier period of freezing becomes excessive after the core has been pumped which causes a considerable amount of splashing of the water remaining in the can and builds a40 ragged edge of ice on the ice block, and also leaves an objectionable hole in the center. I have discovered that it is very advantageous to reduce the air volume within the drop tubes after the cores have been pumped.

This air valve 63 will allow for more uniform45 freezing at the top of the block of ice, thereby causing a more even surface to be produced and reducing the final freezing time of the block.

The valve stem 60 is enlarged at 61 centrally45 within a bore 62 in the valve 63. The stem is reduced in diameter at 64 to form a shoulder 65 against which packing 66 is forced by a plug 67.

The plug 67 is screwed into a threaded aperture50 68 thereby forcing the packing downwardly against a shoulder 65 of the valve stem and a shoulder 69 of the valve body by the lower surface 70 of the plug 67, and outwardly against55 the interior wall 71 of the valve body as clearly shown in Figure 8.

Above the plug 67 the stem is further reduced at 72 for the reception of a stem-operating handle 73.

The bore 62 in the valve body forms a chamber60 74 into which air is admitted from the hose connection and coupling through an opening 75 in the valve body and into which the tapered end 26 of the coupling is inserted. The bottom 77 of the chamber 74 within the valve forms a seat 78 into which the lower end 79 of the valve stem is placed.

I provide the enlarged portion 61 of the valve stem with an interior bore 80 which communicates with a discharge or outlet opening 81 within a downwardly directed threaded nozzle 82.

The enlarged portion 61 of the valve stem is initially provided with a drill spot 83, Figure 11, in order that exact location may be made for75 the placing of the valve stem in the valve and

also as a convenient means of allowing the openings 84 in the valve stem to be drilled to any desired size to suit any pressure required after the core water has been removed.

The holes 84, 84' are so proportioned to the80 quantity of air required as to give a predetermined minimum aerating flow within the can basket lateral 31. For example if there be but four cans to a basket—and therefore to a lateral—these holes will be made smaller than would be85 the case if there were six cans to a basket. Preferably they are cut into the interior of the lateral but not through.

For the normal full flow of air much larger90 openings are desirable. Since the space across the inlet at 85 is narrow I prefer to use two or more openings 86 in line lengthwise of the valve, which in one valve position are sealed by the shell from edge 87 to edge 88 (Figure 9) with the valve in a position turned a half turn from that95 of Figure 9 to close air off entirely at the valve.

As will be seen the valve when opened will normally present full openings 86 for air flow, the flared openings 84, 84' being closed against bearing faces 89 and 90 of the valve body. With the100 quarter turn in either direction one of the openings 84, 84' will be exposed for air inlet to the bore of the tubular valve and the other will be exposed to the dead space 91.

The can baskets are spaced in the frame by any105 suitable means such as by bars 92 and care is taken to prevent interference with the air feed because of moisture in the air. This protection takes two forms. The air in the header is heated by a steam pipe 93 so as to decrease the humidity110 and reduce the chance of condensation entirely.

In operation the air is automatically turned on when fitting 39 is inserted within the body 38 pushing the ball valve 43 to position seen in Figure 5. Because the end of this fitting forms a115 complete ring at 94 not substantially interrupted by lateral apertures 49 there is very little tendency to pit the ball valve and substantially no wire drawing takes place, the flow of air being removed from the surface of the ball and being120 carried beyond it to the lateral openings instead of initially taking place along the surface of the ball as would be true if the tapered end of the fitting terminated in a serrated or notched surface. This avoidance of air passage along the125 surface of the ball is regarded as of considerable value.

The air from the main lateral 24, in Figures130 1 to 5 is thus turned on by the valve 38 to the controlling valve 63 and to the can basket lateral 31. In Figures 14 and 15 the valve 38 of Figure 5 is omitted and the air is connected directly from the air header 20 through the controlling valve 63 to the can basket lateral 31. In either event from the can basket lateral the air135 passes through the L's and flexible tubes 56 to the drop tubes 28. It is quite desirable to control the entire can basket lateral air supply by a single valve rather than to have a separate valve in each air connection. This is not only be-140 cause of reduction in the number of valves but because of the better location for the valve at the connection to the lateral than at the individual lateral tubes to the drop tube.

When the water is partly frozen in the cans145 of the basket and the unfrozen water has been greatly reduced in quantity I find that I can reduce the freezing time and froth which otherwise is present and improve the character of the block of ice by cutting down the quantity of air to the150

150

cans and can quickly, conveniently and reliably do this to best advantage by cutting down the air to the entire group of cans in a basket at the same time to a predetermined fixed quantity, as by a valve 63 having definite valve openings of different size. Moreover though the openings 84 on opposite sides across the hollow valve stem 60 might be made of different size to give a choice of sizes in the individual installation according to whether the valve be turned a quarter turn right-handedly or left-handedly I find that this additional choice of control supplies is not ordinarily necessary and therefore does not ordinarily justify the possible confusion in the minds of the operators as to the direction of turning. The turning of the handle is always clockwise and one side is painted white to instantly indicate the wide open position.

It will be evident that the character of the curve of the spaced bracket arms, concave facing upwardly and downwardly, permits much more nearly direct connection between a low elbow nozzle fitting into the top of the tube ferrule than would otherwise be the case and gives greater opportunity for positioning, manipulating and adjusting the connections than was given by prior straight brackets.

It will be evident that the connection from the header through a general lateral valve to the can basket lateral has its advantages in separate control of the flow of air independently of the flow of a predetermined quantity of air, but that with the use of a quantitative control valve, such as that shown in Figures 8 and 9, the additional lateral and the general shut-off valve 38 can be omitted, using the valve of Figures 8 and 9 for the double purpose of a shut-off valve and quantity-control valve. However, the value of the valve 38 of Figure 5 as a check valve automatically operated is then lost.

In view of my invention and disclosure variations and modifications to meet individual whims or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In an air-agitating system for ice cans, an air tube hanging in the ice can and delivering air to the lower part of the can, a support swingably supporting the air tube, an air delivery system therefor including a lateral feeding the tube and a valve in the system at the lateral inlet having a plurality of passages of different sizes selectively open whereby predetermined different pressures of air can be maintained selectively in the discharging tube.

2. In a can basket construction, a header, a basket frame, a plurality of cans in the basket frame, a can basket lateral for the basket, air tubes swingably supported in the cans, and air connections between the tubes and the lateral, other air connection between the lateral and header including a valve having definitely variant openings whereby one opening can be provided for the earlier part of the freezing and a definite smaller opening can be provided, without altering the connections from the tubes to the lateral and when the freezing has largely been completed.

3. In a can basket construction, a header, a bas-

ket frame, a plurality of cans in the basket frame, a can basket lateral for the basket, air tubes swingably supported in the cans, and air connections between the drop tubes and lateral and other air connection from the lateral to the header, said other connection including a valve having definitely variant openings whereby full opening between the lateral and header can be provided for the earlier part of the freezing and a definite reduced opening can be provided without altering the connections from the lateral to the cans and when the freezing has largely been completed.

4. In a can basket construction, a header, a basket frame, a plurality of baskets therein, each basket including a plurality of cans, a lateral for the basket frame, a can basket lateral for each basket, air tubes swingably supported in the cans and air connections between the tubes of each basket and the basket lateral and between the basket lateral and header through the basket frame lateral, the said connections including a valve at the inlet of each basket lateral and out of the basket frame lateral and having definitely variant openings whereby full opening can be provided for the earlier part of the freezing and a definite reduced opening can be provided without altering the connections from the tubes to the lateral and when the freezing has largely been completed.

5. In an ice refrigerating system, a plurality of cans in series, a lateral for the cans, air tubes swingably supported in the cans and air connections between the tubes and lateral, including a valve having definitely variant openings controlling air flow to a plurality of drop tubes whereby full opening can be provided for the earlier part of the freezing and a definite reduced opening can be provided without altering the connections from the tubes to the lateral and when the freezing has largely been completed.

6. In an air agitating drop tube system for ice cans, an air supply lateral, a bracket having clamp means, an arm upon the clamp means and having a portion extending downwardly from said clamp means, a portion upon said arm extending outwardly and approximately horizontally, a ferrule mounted upon the free end of the last mentioned portion of the arm, a drop tube suspended in a vertical position from the ferrule, an elbow having a lower vertical portion engaging the ferrule, a flexible tube connected with the upper portion of the elbow, and said outwardly extending portion of the arm having sufficient length to provide a clearance space between the elbow and said downwardly extending portion of the arm to permit the free rotation of the elbow relatively to the ferrule and the flexing of the flexible tube.

7. In an air agitating drop tube system for ice cans, an air supply lateral, a bracket having clamp means upon the upper end thereof, a drop tube, a ferrule secured upon the upper end of the drop tube, means upon the lower end of the bracket arranged to receive the ferrule and for suspending the drop tube in a vertical position within the can, an elbow having a vertical portion engaging the ferrule and an approximately horizontal portion, a flexible tube connected with the last mentioned portion of said elbow and with said lateral, said bracket having the free end thereof which is located adjacent to the ferrule gradually curved and extending approximately parallel with the last mentioned portion of the elbow and in spaced relation to the latter and providing free

space for the elbow to be rotated relatively to the ferrule when being inserted and removed from the ferrule, and said bracket having an abruptly upwardly curved portion located adjacent to the 5 end thereof upon which said clamp means is located.

8. In an air agitating drop tube system for ice cans, an air supply lateral mounted above the cans, a bracket having clamp means secured to 10 the lateral, said bracket having an S-shaped arm, said arm having an upwardly curved portion thereof secured to the clamp means, a drop tube, a ferrule secured upon the upper end of the drop tube, support means upon the free end 15 of the arm and occupied by the ferrule and arranged for supporting the drop tube in a vertical

position within the can, an elbow having a lower portion rotatably mounted in the ferrule in axial alignment with the drop tube, a flexible tube connected with the upper portion of the elbow and connected with said lateral, said arm having an opening formed through the medial portion of the same and occupied by the flexible tube, said arm arranged with a flat portion thereof located adjacent to the ferrule, and said arm having a gradually upwardly curved portion thereof located at a sufficient distance from the ferrule to provide a free space for the rotation of the elbow relatively to the ferrule and for the flexing of the flexible tube between the arm and the ferrule. 80 85 90
